UNITED STATES PATENT OFFICE.

JOHN F. CAVANAGH, OF MERIDEN, CONNECTICUT, ASSIGNOR TO THE CONNECTICUT TELEPHONE & ELECTRIC COMPANY, INC., OF MERIDEN, CONNECTICUT, A CORPORATION OF CONNECTICUT.

ELECTRIC SWITCH.

1,328,562.

Specification of Letters Patent.

Patented Jan. 20, 1920.

Application filed August 15, 1918. Serial No. 250,019.

To all whom it may concern:

Be it known that I, JOHN F. CAVANAGH, a citizen of the United States of America, residing at Meriden, Connecticut, have invented a new and useful Electric Switch, of which the following is a specification.

My invention relates to lighting switches and switches of the like character used in automobiles and designed to be rendered inoperative when the machine is left unattended.

The objects of my invention have been to provide a particularly simple, inexpensive and at the same time, efficient switch of this character.

Briefly stated, the invention may be said to reside in the combination with suitable switch contacts, of a removable controlling member therefor in the nature of a plunger and having both an "off" and an "on" position, while associated with the contacts. This structure enables the entire removal of the controlling plunger, or plug, for the purpose of rendering the switch inoperative and permits also of the plug remaining associated with the contacts in the "off" as well as the "on" position.

Other features of the invention and details of construction will appear as the specification proceeds.

In the accompanying drawing I have illustrated in a practical form one embodiment of the invention, wherein:

Figure 1, is a front view of the switch as applied to a suitable face plate showing the same in the operative position.

Fig. 2, is a similar view with the controlling plug member removed and the switch in inoperative position.

Fig. 3, is a detail view of the detached controlling plug.

Fig. 4, is a sectional view of the switch taken substantially on the plane of the line 4-4 of Fig. 1.

In the particular structure disclosed the switch base 5 is in the form of a hollow open ended tubular member of insulating material partially closed at the front or open end thereof, by a plate or disk 6 carrying a tubular guide sleeve or bushing 7 projecting into the hollow base.

Within the hollow base are the separate spring contact fingers 8 and 9 and supported in this instance by being secured to the closed rear wall of the base.

The removable plug or plunger is shown constructed with a smooth shank portion 10 slidably working in the tubular guide 7 and near its inner end with reduced or annularly grooved portions 11 and 12 separated by an intervening ridge 13. The reduced portion 11 is shown made of insulating material and the other reduced portion 12 is shown made of conductive material and is mounted on the insulating material between the ends of 65 the latter. When therefore the conductive portion is engaged with the opposed springs, as in Fig. 4, a circuit will be closed across the switch contacts and when the plunger is partly withdrawn to engage the insulating 70 portion 11, with the spring contacts, the circuit will be interrupted across the switch contacts. The switch plunger will be retained in either the "on" or "off" position by the engagement of the contacts in the 75 reduced or annularly grooved portions described and a snap action of the plunger in passing from one position to the other is insured by reason of the raised ridge 13 between the annular grooves which ridge separates the conducting and nonconducting portions 12 and 11 respectively.

The structure described thus enables the switch as an entity being left in either the "on" or "off" position and in addition it is 85 possible to entirely withdraw the plug and wholly disconnect the same from the switch contacts. To accomplish this it is only necessary to exert sufficient pull on the plug to overcome the holding tension of the 90 spring contacts. If the switch is in the "off" position when the plug is withdrawn, the plug is merely withdrawn from engagement with the spring contacts in the end reduced portion 11, and if the switch is in 95 the "on" position when the plug is withdrawn, the plug is simply pulled longitudinally to carry both the reduced portions 11 and 12 out of engagement with the holding contacts.

The plug is reengaged with the switch by simply inserting it through the tubular guide 7 and pushing it inward until it snaps into engagement with either the insulating portion or the conducting portion, according as to whether it is desired to simply replace the plug or to establish a circuit by means of the switch. The end of the plug is preferably more or less pointed as indicated at 14 to facilitate entry between the spring 110

contacts and this point or conical end portion is preferably made of insulating material, as indicated, so as not to form a bridge across the switch contacts when the plug is being entered. A suitable finger hold such as the enlargement or head 15 may be provided at the outer end of the plug for facilitating handling or operation of the same.

The switch may be mounted in various 10 ways. In the illustration it is shown secured as by means of screws 16 on the back of a face plate 17.

My invention, it will be seen, provides a practical and at the same time very simple 15 and inexpensive switch for controlling a circuit, which can be rendered entirely inoperative by simply withdrawing the plug and which however may be left in the "off" or open-circuit position with the plug still in 20 place. This is very desirable for automobile lighting where the switch should be in condition for instant operation by the driver of the car and should be capable of being rendered inoperative when the driver 25 leaves the car.

I claim:—

1. In a device of the character described, a base, a face plate attached to one end of said base and having a guide aperture for a 30 plug, spring contacts mounted in said base

in spaced relation to each other, terminals for said spring contacts, a plug for insertion in said aperture and guided thereby, said plug having an insulating portion near one end, said portion having an annular depression, a portion of conducting material mounted on said insulating portion between the ends of the latter and having an annular depression, said plug being of such conformation that it may be entirely withdrawn 35 from said guide aperture, and said plug being releasably held in the off or the on position by means of the spring contacts engaging in said annular depressions.

2. As an article of manufacture, a plug 45 for electric switches having near one end a portion of insulating material, said portion having an annular depression, a portion of conducting material mounted on said portion of insulating material between the ends of the latter and having an annular depression, a relatively smooth portion adjacent said portion of insulating material, said smooth portion being of a diameter at least as great as any diameter of the plug between the 50 relatively smooth portion and the aforesaid end of the plug, and a head upon the end of the plug remote from said first mentioned end.

JOHN F. CAVANAGH.
